(57) **CLAIM**

The ornamental design for a diffuser for a hair dryer as shown and described.

DESCRIPTION

Diffuser for a hair dryer

Fig. 1.1 is a perspective view of a diffuser for a hair dryer showing my new design;

Fig. 1.2 is another perspective view thereof;

Fig. 1.3 is a front view thereof;

Fig. 1.5 is a top view thereof;

Fig. 1.6 is a right side view thereof;

Fig. 1.7 is a bottom view thereof; and

Fig. 1.8 is a left side view thereof.

The portion of the design shown in the color red illustrates structure that forms no part of the claimed design.
